Primary Examiner — Robert M Spear*Assistant Examiner* — Marissa J Cash(74) *Attorney, Agent, or Firm* — Marshall, Gerstein & Borun LLP**(57) CLAIM**

The ornamental design for a flying toy, as shown and described.

DESCRIPTION

FIG. 1 is a three-quarter front view of a flying toy that has the design.

FIG. 2 is a front view of the flying toy.

FIG. 3 is a rear view of the flying toy.

FIG. 4 is a left-side view of the flying toy.

FIG. 5 is a right-side view of the flying toy.

FIG. 6 is a top view of the flying toy; and,

FIG. 7 is a bottom view of the flying toy.

Any elements of the flying toy that are not clearly disclosed in the drawings are not part of the claimed design.

The broken lines in FIG. 7 show elements of the flying toy that form no part of the claimed design.
